CLAIM

The ornamental design for a combined automatic computerized wave detecting and monitoring machine for analyzing patient symptoms and determining prescriptions, as shown and described.

DESCRIPTION

FIG. 1 is a perspective view of a combined automatic computerized wave detecting and monitoring machine for analyzing patient symptoms and determining prescriptions, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front elevational view thereof, wherein the foot rest is pushed into the bottom of the panel table and the chair is shifted;

FIG. 9 is a perspective partial view thereof, showing the bottom of the panel table; and,

FIG. 10 is a perspective partial view thereof in a state for use by a child.
